PICKUP BALER

Albert R. J. Luke, Toronto, Ontario, Canada, assignor to Massey-Harris Co. Ltd., Toronto, Ontario, Canada, a corporation of Canada

Application March 5, 1949, Serial No. 79,800

2 Claims. (Cl. 56—343)

1

The present invention relates to novel means for picking up hay, straw and the like that has already been cut, wind-rowed or swathed and move it to the baler and having other means for binding the material in bales.

The principal objects of the present invention generally stated, are to provide a device of the character which is simple, light, efficient, easily manufactured at low cost and durable.

Pick up balers of the character generally have a packing chamber, a packing plunger, a wad board and a wad board well. The wad board oscillates to press the hay into the well when the packing plunger is largely out of the well and from which the hay is pressed by the oscillating packing plunger into the packing chamber largely when the wad board is out of the well.

A novel feature of the present invention is the means provided for conveying wads of hay intermittently into or over the wad board well, the wad board cooperating with the conveyor to intermittently force the wads of hay in front of the packing plunger while the conveyor is returning to a position for engaging the next wad of hay.

To these and other useful ends not already enumerated, my invention consists of parts, combinations of parts or their equivalents and mode of operation as hereinafter described and claimed and shown in the accompanying drawings in which:

Fig. 1 is a top view of my improved baler showing the needles during the period of dwell and the packing plunger in its most forward position not showing the wad board and its connecting parts.

Fig. 2 is a right side elevational view of the device as shown in Figure 1.

Fig. 3 is a left side elevational view of the device as shown in Figure 1.

Fig. 4 is a rear view of the device illustrating the transverse conveyor mechanism by dotted lines.

Fig. 5 is an enlarged view of the conveyor with the rear panel of the conveyor trough removed and illustrating the hay engaging means by full lines while moving toward the wad board well, the dotted lines illustrating the hay engaging means while moving away from the wad board well, with the wad board illustrated in its uppermost position in full lines and in its lowest position by dotted lines.

Fig. 6 is a fractional top view of the device showing in full lines the needles and twine or wire in their neutral or inoperative positions or during the period of dwell, and the needles and

2

twine are shown by dotted lines after the bale has been packed and is held ready for tying.

Fig. 7 is a transverse sectional view of the transverse conveyor taken on line 7—7 of Figure 1 with its operating parts in the position shown in Figure 1.

Fig. 8 is a sectional end view of the right side of the packing chamber taken on lines 8—8 of Figure 2 illustrating the means for restricting the free rearward movement of the bales.

Fig. 9 is a diagrammatic drawing illustrating the power connection to the various operating parts of the device as viewed from the left side of the device.

Fig. 10 is another diagrammatic drawing viewed from the right side of the device and similar in purpose to Figure 9.

Fig. 11 illustrates fractionally the dual means for driving the operating parts of the device, not including the wad board and packing plunger.

Fig. 12 is an enlarged right hand elevational end view of the pick up device.

As thus illustrated the main frame is in its entirety designated by reference character A. The carrying wheels are designated by reference character B. The engine is in its entirety designated by reference character C. The pick up device is in its entirety designated by reference character D, the transverse conveyor is in its entirety designated by reference character E, and the packing chamber is in its entirety designated by reference character F.

The forward end of member A is provided with an extension frame 10 having suitable means 11 at its front end for connecting the device to the draw bar of a tractor. I preferably provide an engine C for furnishing power and mount this engine on extension frame 10 as illustrated in the figures, the engine having a driving pulley

12 (see Figure 3). A belt wheel 13 is rotatably mounted on frame A by means of a shaft 14. A crank shaft 15 is rotatably mounted on frame A in front of shaft 14. Shaft 14 has a pinion 16 (see Figure 3) and crank shaft 15 has a gear 17 which meshes pinion 16. Belt wheel 13 is driven from engine C by means of a belt 18 and in the direction of the curvilinear arrow 19 (see Figure 3). Thus shaft 15 will be driven in the opposite direction from shaft 14 as indicated by a curvilinear arrow. Shaft 15 has a crank

20 (see Figures 1 and 3). The rear end of member A is shaped to provide a packing chamber F by means of upper and lower members 21 and 22 (see Figure 3). The front end of this packing chamber extends to

55

a wad board well 23; the sides and bottom of this well are in alignment with the sides and bottom of packing chamber F. The front end of this well has an opening which is in alignment with packing chamber F. A packing plunger 24 (see Figures 1 and 3) is provided and adapted to oscillate through the wad board well 23 and extend slightly into the packing chamber when in its rearmost position. Packing plunger 24 is adapted to be only slightly within the well 23 when in its foremost position. Packing plunger 24 has a connecting rod pin 25 (see Figures 1 and 3). This pin and crank 20 are operatively connected together by connecting rod 26.

I provide ratchets (not shown) on opposite sides of packing chamber F and directly in rear of wad board well 23 adapted to be spring held against the packed hay in the packing chamber so as to prevent the hay from moving forward by expansion or otherwise when the packing plunger is not in contact with the packed hay.

In addition to the means for holding the packed hay from moving forward by expansion or otherwise, I provide means for preventing the packed hay or completed bale from moving freely rearward in the following manner:

I position spaced apart bars 30-30 in the side spaces between members 21 and 22 (see Figures 2 and 3) and preferably hinge these members at their front ends to the packing chamber a short distance in rear of the wad board well. Members 21 and 22 are secured together near their rear ends by means of brackets 31-31. The brackets are shaped as shown in Figure 8 and have secured to their centers, nuts 32 through which bolts 33 are screw threaded, having heads and cross bars 34 as a gripping means for pressing members 30 against the baled hay as follows:

Brackets 35 secure members 30 together and the ends of bolts 33 rest on these brackets as shown. These bolts extend through plates 36 which are secured to the inner lips of members 30. Thus without other means, members 30 will be held in vertical position and pressed against the packed hay so as to retard its rearward movement and assist the packing plunger to firmly pack the hay in the chamber.

A toothed wheel 37 is caused to contact the packed hay and turn its shaft 38 which is rotatably mounted on member 21. This toothed wheel has the proper diameter so that when the packed hay is formed in a suitable length bale, a cam on shaft 38 will operate a trip 39 and set the tying mechanism in motion which takes place when the needles are in the position shown by full lines in Figure 6.

I have already described the means for packing the hay into bundles and will now describe the means for tying the bundle into a bale.

It will be understood that I may elect to use a tying mechanism suitable for wire or twine for completing the bale and that the manner of tying the twine or twisting the wire, forms no part of this invention; therefore detailed drawings and description are not considered necessary. This tying mechanism is designated in its entirety by reference character G in Figure 2.

Throughout the specification and claims "hay" will now be used to designate hay and straw or the like. "Binding material" will now be used to designate either wire or twine and "knotted" will now be used to designate the means for tying the twine or twisting the wires together and cutting the bales loose.

It will be understood that I may elect to fur-

nish power for operating my device from the power take off of the tractor. The pick up device should travel faster than normal when the machine is moved over the ground faster than normal. I therefore provide dual means whereby suitable overrunning clutches or ratchets are used through which to drive the pick up device, either from a ground wheel, the engine or the power take off shaft of the tractor as will hereinafter appear.

I will now describe my transverse conveyor E. Wad board well 23 is closed on its left side by a panel 45, at its rear side by a panel 46 and at its front side by a panel 47 (see Figures 1 and 3). Panels 46 and 47 extend to the right forming the front and rear panel of member E terminating at an end panel 48 and having a bottom plate 49 thus forming a conveyor trough. The front panel 47 is open for a considerable height from plate 49 and for the length of the outlet from the pick up device D forming an inlet to the bottom of the trough.

I provide novel means for moving the loose hay from the bottom of the trough into the wad board well as follows:

Near the top of the trough I transversely space and rotatably mount double throw crank shafts 50 and 51, the cranks on each shaft being positioned relative to each other about as shown in Figure 5, and, considerably less than 180 degrees apart, the reason for which will hereinafter appear.

The rear pair of cranks on shafts 50 and 51 are in alignment (see Figure 1) and being operatively connected together by means of a walker bar 52 and bearings 53-53. Another walker bar 52 is similarly connected to the front pair of cranks; therefore because of the position of the cranks on shafts 50 and 51, bars 52 will act to turn shaft 51. The driving connection to shaft 50 will hereinafter appear.

It will be seen by viewing Figure 5, that as the shafts turn as indicated by curvilinear arrows, spaced depending pairs of fingers 54 will swing down and toward the wad board well and up and from the wad board well. Thus the hay on plate 49 will be moved to the left and over the wad board well and while the wad board is largely out of the well and while the fingers are traveling to the right they are a considerable distance above plate 49. There is therefore, no interference with the free movement of the hay from the pick up device into the trough and under the fingers.

I will now describe the operation of my wad board. A post 60 is supported and bracketed on member A (see Figure 3). Wad board 61 is oscillated on post 60 by means of links 62 and 63 in a manner, whereby the wad board will be directed into the wad board well, and the timing is arranged so the wad board is in its lowest position or in front of the packing plunger 24 when it is in its foremost position or substantially out of the well, as is the practice in hay balers of the character.

Link 63 is extended forwardly and downwardly as at 64, the lower end of which is operatively connected to connecting rod 26 by means of another connecting rod 65, which is at its rear end pivotally connected to connecting rod 26 as at 66. Thus it will be seen that as the connecting rod is oscillated by crank 20, wad board 61 will oscillate generally vertically and be moved into the wad board well as the packing plunger 24 moves out of the well or vice versa. It will be noted

that the wad board and packing plunger, transverse conveyor, knotted and needles are positively driven by engine C as will hereinafter appear.

It will be understood that I prefer to turn shafts 50 and 51 two times for every turn of the packing plunger crank, or for each cycle of operation of the wad board, shafts 50 and 51 being suitably timed for the purpose.

I will now describe my novel and dual means for driving the transverse conveyor, pick up device, needles and the knotted mechanism.

I provide a gear box 67 into which shaft 15 extends and is rotatably mounted having secured to its end a bevel gear 68. A shaft 69 is rotatably mounted in gear box 67, both ends protruding and having secured thereto a pinion 70 adapted to mesh with gear 68. A chain sprocket 71 is secured to the protruding end of shaft 69. I provide another gear box 73 into which shaft 72 extends and is rotatably mounted and has secured to its end a bevel gear 74. A shaft 75 is rotatably mounted in gear box 73 and has secured thereto a beveled pinion 76 which is adapted to mesh with bevel gear 74. The left end of shaft 75 protrudes and has secured thereto the driven member of a slip clutch or ratchet 77. On the outer end of shaft 75 I rotatably mount a chain sprocket 98. Member 78 carries the driver member of the slip clutch 77. A chain 78' forms an operating connection between sprockets 71 and 78. It will be seen therefore that shaft 72 is free to turn faster than is required by its connection to shaft 69, however when its speed drops below a certain point slip clutch 77 will be engaged and shaft 72 driven by shaft 69.

I mount an overrunning clutch or ratchet 79 on the left hand wheel B (see dotted lines in Figure 3) and secured to this clutch a chain sprocket (not shown). On the left end of shaft 72 I mount a sprocket 80 which is operatively connected to the sprocket on overrunning clutch 79 by means of a chain 81. A shaft 82 is rotatably mounted on member A having a sprocket 83 which is engaged by chain 81 and driven in the direction indicated by curvilinear arrow in Figure 9, the chain extending over an idler sprocket 84 which is slidably adjustably mounted on member A for adjusting the tautness of chain 81.

It will be seen that shaft 72 may be driven by shaft 15 unless driven faster by overrunning clutch 79 and that the pick up device D may be driven by the engine through shaft 15 depending upon the speed the machine travels over the ground. It may be said that when the machine is traveling over the ground above normal speed, that member D will travel proportionally faster than normal and independent of the engine speed.

I will now describe my operating connection to the transverse conveyor and to member G.

A shaft 90 is rotatably mounted on member A and in the position shown in Figure 4. This shaft is operatively connected to shaft 69 by means of two universal joints 92 and an intervening shaft 91. An operating connection is made between shaft 90 and shaft 50 by means of sprockets 93 and 94 and a chain 95 (see Figure 4). I provide a vertically positioned shaft 96 (see Figure 2) which acts as a driver for the tying mechanism G and for operating the needles as shown:

Shaft 96 is operatively connected to shaft 90 by means of a pinion 97 and a gear 98. Means are provided (not shown) whereby normally

shaft 96 will only operate when link 39 forms an operating connection between shafts 90 and 96 and whereby the fingers will be operated at the same time member G acts to complete the bale. These operations are as follows:

A novel feature of applicant's device is that there is a period of dwell provided for the needles 100, when they are in the position shown by full lines in Figures 1 and 6.

The timing of member G and the needles are a very important matter. When the needles begin to move into the machine from the position shown in full lines, packing plunger 24 has started its rearward movement, after which the needles enter the slots 101 in this member. The rear end of needles 100 are mounted on a shaft 102, the shaft being rotatably mounted on member A (see Figure 3) by means of bearings 103-103, the shaft extending a distance below the lower bearing and having secured thereto an arm 104. A crank 99 is mounted on the lower end of shaft 96 and is operatively connected to arm 104 by means of links 105, 106 and 107.

In Figures 1 and 6, these links are shown diagrammatically and when needles 100 are in the position shown by dotted lines, the links are in the position shown by dotted lines and when the needles are in the position shown by full lines the links are in the position shown by full lines.

In the former the crank is in the extreme right position (see Figure 6) and in the latter, crank 99 is in the left position as shown. It will therefore be seen that a joint 108 and link 107 permit a period of dwell for the needles during about one-third of a turn of crank 99, therefore the movement of the needles is confined to about two thirds of a turn of the crank so that by positioning shaft 96 as shown, the needles will be permitted to operate without interference and be properly timed to accommodate the movements of the wad board, packing plunger and tying mechanism.

By scrutinizing Figure 6 the object of the shape of needles 100 will be apparent. Full line 115 illustrates the position of the twine or wire as it leads from the roll or ball through the needles and to the bale, and from the bale to the tying mechanism and while the tying takes place the wire or twine is shown by dotted lines 116. It will be seen that the wire or twine will be stretched tightly over the end of the bale which is designated fractionally by reference numeral 117. It will also be seen that after the tying has been completed and the bale cut free, it will be permitted to expand very little before the slack between the bale and tying mechanism is taken up. Therefore the tying material will be taut on the completed bale after it has been cut free and the wire or twine will again assume the position shown by full lines when the needles are in the position of dwell.

It will be seen that the position of shaft 102, shape of the fingers 100 and the position of member G are important matters; furthermore the dual drive for members D, E and G is important because when the machine is traveling rapidly, member D must turn rapidly in order to handle the hay. On the other hand if the machine travels more slowly than normal or if it is not moving at all, all of the operating parts of the machine may be kept moving by engine C.

I will now describe my novel pick up elevator D.

Ground wheel axle 118 is mounted on members A and E. The pick up device D is hinged adjacent axle 118 as at 125 so it may be raised and

lowered on this pivot as will hereinafter appear:

Transversely spaced arms 126 extend from pivots 125 upwardly and forwardly and are rigidly connected preferably to a transverse tube 127 (see Figure 12), the tube having secured thereto transversely spaced apart arms 128 between which the rotor of the pick-up is positioned having a shaft 129 which is rotatably mounted in bearings 130 which are secured to arms 128. Shaft 82 is operatively connected to shaft 129 by means of another shaft 131 and suitable universal joints. The rotor is formed by means of spaced apart discs 132—132 secured to shaft 129. Between the right hand disc 132 and its arm 128 and secured to the arm I mount a disc 133. Preferably six tubes 134 are rotatably mounted in circumferentially spaced relation in discs 132, the right hand ends of these tubes protruding through members 132 and having secured thereto levers 135, each having a roller 136 which is adapted to ride on the periphery of member 133.

Each tube 134 is provided with a number of spaced apart fingers 137 (see Figures 1 and 12). Between each circumferential row of fingers I position a stripper plate 138 which is shaped as illustrated in Figure 12, one end of each extending over a plate 139 which acts as a forward extension to plate 48. Each tube 134 is preferably provided with a spring (not shown) adapted to yieldingly cause rollers 136 to ride over the periphery of disc 133. The cut away portion 140 of the disc 133 is adapted to cause the fingers 137 to disengage themselves from the hay as they pass downward between the strippers and this cut away portion is adapted to swing the fingers forward as they approach the ground surface so as to engage and lift the hay from the ground as the fingers contact the windrow of hay.

I provide wind guards 141—141 and preferably position one above each stripper 138, or at least one above every other stripper as follows:

I provide two gathering guards 142 and preferably secure them to the outer strippers (see Figure 1). They are also secured to arms 128, these arms being extended forward of members 142 as at 143 and having preferably a transverse bar 144 which extends upwardly at its ends as at 145 and being pivoted to arms 128 as at 146. Members 141 are secured to bar 144 in the position as shown in Figure 12 with their rear ends yieldingly lying on the strippers and terminating largely at the inlet of the transverse conveyor trough and over member 139. Members 145 at their upper ends are connected to members 142 by means of pull springs 141, thus to yieldingly hold the rear ends of members 141 on the moving hay. The front ends of members 141 are curved as illustrated thus to form an easy inlet to the pick up rotor and an easy upward and rearward path between the strippers and members 141. Members 142 act to prevent the hay from spreading and to assist in confining it within the length of the rotor. I preferably provide a lever 150 (see Figure 2) with a connection to the inner member 143 for regulating the height of the pick up rotor D. This lever is preferably mounted on a shaft 151 and is adapted to engage a sector 153, shaft 151 having a lever 154 which extends to the right with a connecting link 155 which is at its lower end connected to the inner extension 143. Thus by manipulating

lever 150, member D may be raised or lowered on pivot 125 and locked into the desired position.

It will be seen that I have provided a pick up hay baler, all of the units of which cooperate to produce a very simple and successful machine.

Clearly minor detail changes may be made in the designs shown of the various parts of my machine without departing from the spirit and scope of the appended claims.

10 I claim:

1. In a pick-up baler of the character described, having a wheel-carried frame, a power source on said frame, a pick-up elevator, a transverse conveyor having an inlet for receiving the hay from the elevator, a wad-board and wad-board well having an inlet from said transverse conveyor, a packing chamber and a plunger therefor comprising in combination, said transverse conveyor comprising a bottom plate with vertically arranged side panels and an outer end panel forming a trough with an inlet from said pick-up elevator, its inner end having an outlet into said wad-board well, a pair of spaced shafts transversely and rotatably mounted on said side walls and a distance above said bottom plate, each said shafts having a pair of cranks, walker bars rotatably mounted on aligned cranks, each having spaced depending fingers adapted to engage the hay discharged from said pick-up elevator and move the hay intermittently into said wad-board well largely when the wad-board is out of the well.

2. In a pick-up baler having a well, a wad board for forcing material into said well by reciprocating in a substantially vertical direction from a raised inoperative position to a lowered position, a pick up mechanism; an improved feeder mechanism for conveying material from said pick-up to said well comprising, a trough, a pair of double throw crank shafts rotatably mounted in said trough, the cranks on each shaft being less than 180° apart to provide an intermittent feed, a pair of walker bars rotatably connected to each shaft, downwardly extending material engaging fingers secured along the length of said bars, means for driving said wad board, means for driving said feeder and so timed and arranged, that the intermittent feed of said feeder occurs when said wad board is in the raised position.

ALBERT R. J. LUKE.
